PROTECTIVE CIGARETTE HOLDER

Frank Skidmore, Oakland, Calif., assignor, by direct and mesne assignments, of one-third to Antonio G. Tassano, Oakland, Calif., and one-third to Richard O'Hara, Alameda, Calif.

Application June 30, 1932, Serial No. 620,237
Renewed May 25, 1936

8 Claims. (Cl. 131—186)

The invention relates to a device as disclosed in my copending application Serial No. 585,911, filed January 11, 1932, designed to provide an individual protective container for a cigarette before use and to serve as a holder and mouthpiece for the cigarette in smoking.

An object of the invention is to provide a holder of the character described, which, while retaining the form and size of the cigarette, is so designed and constructed that should the cigarette be rested on a supporting surface while lighted, contact between the surface and the ignited end of the cigarette will be prevented.

Another object of the invention is to provide means affording the advantage aforesaid, which is in the form of a portion of the holder and so arranged that when not operatively disposed its presence will not be apparent or felt.

A further object of the invention is to provide a holder of the character described which may be made in one size and yet perfectly fitted for cigarettes of different thickness.

A still further object of the invention is to provide a holder with the aforementioned features in which the means for adapting the holder for fit with different sized cigarettes is combined with the means for supporting the cigarette in a manner which considerably facilitates the operative positioning of said last means.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to said drawing:

Figure 1 is a perspective view of the holder of my invention as disposed on a cigarette in a package or case.

Figure 2 is a similar view of the holder as disposed on a lighted cigarette and resting on a supporting surface.

Figure 3 is a developed view of the blank with which the holder is formed.

Figure 4 is a longitudinal sectional view of the holder and cigarette as arranged in Figure 1.

Figure 5 is a view similar to Figure 3 of a blank forming a somewhat modified design of holder.

Figure 6 is a side view of the holder as formed

of the blank shown in Figure 4, and positioned on a cigarette before smoking.

Figure 7 is a perspective view of the modified form of holder disposed as the holder in Figure 2.

As illustrated in the drawing, the holder of my invention is in the form of a covering 2 of a moisture-proof or oil sheet-paper, cloth, or the like, and formed of a blank as shown in Figure 3 into a permanent generally cylindrically shaped member as shown in Figures 1 and 2. The covering is preferably almost the full length of the cigarette 3 about which it is designed to be disposed and the inner diameter of the covering is for a large portion of the length thereof of less than the normal external diameter of the cigarette so that when the latter is disposed within the holder the cigarette will be compressed transversely and firmly held therein. This compression of the cigarette makes possible the use of a covering whose outer diameter is practically no greater than that of the cigarette when without the holder, and in this manner the cigarette including the covering will be no larger than the cigarette alone and therefore may be positioned in the usual cigarette package without in the least decreasing the cigarette carrying capacity of the package.

When the covering is originally positioned on the cigarette, one end of the cigarette and of the covering are coterminous while at the other end the covering is just short enough to leave sufficient of the cigarette exposed to permit gripping by fingers for effecting extraction from the holder. The covering, instead of being perfectly cylindrical, is preferably tapered, see Figure 4, from a larger end 10 to a smaller end 7 with the larger diameter greater than that of the cigarette to permit of the ready insertion of the cigarette in the holder through the end 10, and with the smaller diameter of the holder appreciably less than that of the cigarette so as to effect the decreased thickness of the cigarette as aforesaid for a greater portion of its length, the smaller diameter of the holder, however, being such as not to prevent ready longitudinal movement of the cigarette in the holder in either direction when purposely effected. The taper in the covering or the constriction at an end 7 thereof may be readily provided at the time the covering is rolled into form, by causing one end of the cover member to be rolled in advance of the other. The covering may be rolled into form while the cigarette is contained therein, and maintained in such form by the use of adhesive between contacting faces of the covering, or the covering may be formed sep-

arately and the cigarette thereafter inserted, preferably through the larger end 10 of the covering which is adapted for use as a mouthpiece and extended through the smaller end of the cover 5 for a distance sufficient to permit lighting or grasping.

It will now be clear that with the covering thus held over the cigarette, the latter may be disposed practically entirely within the covering 10 as illustrated in Figure 1, or it may be held there- in with by far the greater portion of the cigarette protruding from the end 7 of the covering, as illustrated in Figure 2. The paper or other ma- 15 terial of which the covering is made, is of such character that the covering will be substantially form retaining. In this manner when the cigarette is extended as last mentioned, the covering may serve as a very efficient holder or mouth- piece for the cigarette, and preferably the paper 20 or material aforesaid is transparent or trans- lucent so that the extent of the cigarette within the covering may be ascertained at a glance. The latter feature is desirable in that it enables the smoker to withdraw the cigarette sufficiently 25 to allow its substantially complete consumption while at all times held firmly in the covering. As previously noted in the use of the covering with the cigarette extended for smoking, the latter is drawn out through the smaller end 7 of the cov- 30 ering so that the most effective grip afforded between the covering and cigarette will be main- tained regardless of the position of the cigarette in the covering. The covering is also quite thin as well as snug-fitting, so that when positioned 35 over the cigarette its own thickness will not ma- terially increase the diameter of the latter. Prefer- ably the material of which the covering is formed is non-inflammable so that should the smoker carelessly throw away the lighted cigarette 40 while still lighted and partially unconsumed, the cigarette will invariably stop burning as soon as the ignited portion reaches the covering. In this way the fire hazard caused by the discarding of lighted cigarettes will be greatly decreased.

45 Since as aforesaid the holder is arranged to snugly fit the cigarette, and as there is usually a variation in the thickness of the different ciga- rettes on the market, means are provided on the holder whereby one size of holder is adapted 50 for use with cigarettes of different thicknesses. This is effectively accomplished by forming a por- 55 tion of the holder partly yielding or resilient as by longitudinally slitting the narrow end 7 of the holder preferably at a plurality of circumferential- 60 ly spaced points. These slits 8 define yielding segments 9 which serve to resiliently engage 65 the sides of the cigarette so as to permit of a cigarette of smaller or larger diameter to be readily accommodated in the holder and retained 70 therein with a like firm grip. In the present in- stance three slits are provided, but it is obvious that any number of slits may be used.

75 Means are provided as part of the holder, for enabling the lighted cigarette when contained in the holder, to be rested on a supporting sur- face without danger of burning or marring such surface. This means in the present embodiment of the invention is of extremely simple form and comprises a tongue 12 extending longitudinally from and in conformity with the holder at the end 7 in such manner that in its inoperative po- 80 sition it will lie against the side of the cigarette in the same manner as the contiguous portions of the holder. The tongue 12 is preferably of a 85 width about equal to the diameter of the holder.

thereat, and has provided at the juncture there- of with the main body of the holder a scored or other weakened line 13 so that when desired the tongue may be readily bent outwardly to a po- 90 sition more or less at right angles to the axis of the holder. It will be evident that with the tongue in the angular position aforesaid, the holder may be rested on a surface such as a table top or the like, by contact therewith of the large end 10 of the holder and the forward edge 14 of the tongue. In this manner the smaller end 7 of the holder will be held in an elevated position, and thus with the cigarette in the holder the lighted end of the cigarette will be held free 95 and clear of the surface aforesaid and any dam- age or burning of said surface by contact with the burning tobacco will be avoided. It will thus be clear that the holder of my device provides a considerable safety factor in the smoking of the cigarette. As a means of strengthening the 100 tongue, the blank of which the holder is made, is preferably formed wide enough to provide at the end 7 an overlap along the longitudinal edges equal at least to the width of the tongue, and as clearly shown in Figure 3 a tongue portion is 105 provided on each of the overlapping parts so that when the blank is rolled up the tongue will be formed of a double thickness of the material comprising the holder. In order to facilitate the ready bending of the tongue, the side edges there- 110 of are aligned with the slits 8, thus making the tongue in this embodiment as an extension of one of the segments 9. A band 16 at the larger end of the holder serves not only as a convenient mouthpiece but as an effective reinforcement 115 for the holder.

In the somewhat modified form of the holder 2' illustrated in Figures 4 to 6, a tongue 12' is provided at the outer end of each segment 9'. With this arrangement when each tongue is bent 120 outward, a circular extension is in effect provided so that the spacing of the lighted end of the cigarette will be assured regardless of the position in which the holder is rested on the supporting 125 surface.

I claim:

1. In an individual protective covering and holder for a cigarette, a sleeve tapered uniformly from one end to the other and having its opening at the larger and smaller ends of greater and lesser diameter respectively than the normal diameter of the cigarette, the portion of the sleeve at and adjacent the smaller end being provided with slits extending longitudinally inwardly from said end, thereby rendering said 130 smaller end resiliently expandable.

2. In an individual holder for a cigarette as characterized in claim 1 wherein a portion of said sleeve intermediate adjacent slits is de- 135 signed to be moved from a position resiliently 140 pressing against said cigarette to a position to hold said end spaced from a supporting sur- face when the sleeve is rested thereon.

3. In an individual holder for a cigarette, a sleeve of flexible material arranged to have the 145 cigarette inserted therein, and means formed as a part of said sleeve adjacent an end thereof arranged in one position to lie flat against the side of and resiliently grip the cigarette and in another position to be extended outward at sub- 150 stantially right angles from the side of the ciga- rette whereby on resting the holder by said means said end may be spaced from the sup- porting surface.

4. In an individual holder for a cigarette, a 155

substantially cylindrical sleeve formed of a flexible material and having one end longitudinally slitted at transverse points to provide a resiliently expansible end portion and at the same time to define a tongue, said tongue normally engaging the sides of the cigarette along substantially the entire inner surface of the tongue and being arranged to be bent angularly outward at substantially right angles from its normal position to form a support for the holder.

5. In an individual holder for a cigarette, a substantially cylindrical sleeve of flexible material and formed with a portion thereof of a double thickness of said material, said tube being tapered from substantially one end to the other with the smaller and larger ends respectively of lesser and greater diameter than the normal diameter of the cigarette, the portion of the sleeve at the smaller end being slitted 10 longitudinally to define circumferentially aligned segments, one of said segments being disposed at said portion of double thickness and extended longitudinally of the sleeve to define a tongue arranged to lie against the sides of the cigarette and capable of being bent outwardly transversely of the sleeve to define a means of spacing the adjacent end of the sleeve from a supporting surface when the sleeve is rested thereon.

15 20 25 30 6. In a cigarette holder of the character de-

scribed, a sleeve positionable about a cigarette and having one end longitudinally slitted at transverse points to define a plurality of tongues arranged to resiliently and expansibly grip said cigarette, one of said tongues being longer than 5 the other tongues and arranged for bending in a radially outward direction from the sleeve to form a support for the holder.

7. In a cigarette holder of the character described, a sleeve positionable about a cigarette 10 and having one end longitudinally slitted at transverse points to define a plurality of tongues arranged to resiliently and expansibly grip said cigarette, one of said tongues being longer than and extended from the ends of the other tongues 15 and adapted to be bent outwardly from the cigarette along a line in substantial alignment with the other tongue ends to form a support for the holder.

8. In a cigarette holder of the character de- 20 scribed, a sleeve positionable over a cigarette and formed of flexible material with a portion thereof of a double thickness of said material, said portion being arranged adjacent an end of 25 said sleeve for bending outward transversely of the sleeve to define a means of spacing said sleeve end from a supporting surface when the sleeve is rested thereon.
